Joseph Stevens
by his Atty Thos. J. Sprague

UNITED STATES PATENT OFFICE.

JOSEPH STEVENS, OF TRENTON, MICHIGAN.

CORN-PLANTER.

SPECIFICATION forming part of Letters Patent No. 364,317, dated June 7, 1887.

Application filed December 23, 1886. Serial No. 222,394. (No model.)

To all whom it may concern:

Be it known that I, JOSEPH STEVENS, of Trenton, in the county of Wayne and State of Michigan, have invented new and useful Improvements in Corn-Planters; and I do hereby declare that the following is a full, clear, and exact description thereof, reference being had to the accompanying drawings, which form a part of this specification.

10 This invention relates to certain new and useful improvements in corn-planters.

The invention consists in the peculiar construction, arrangement, and combination of the various parts, all as more fully hereinafter set forth.

15 Figure 1 is a perspective view of my improved machine. Fig. 2 is a vertical longitudinal section through one of the hoppers and its connections. Fig. 3 is a rear view.

20 In the accompanying drawings, which form a part of this specification, A represents an axle, upon which are mounted the traction-wheels B. These wheels are provided with the so-called "ratchet-hubs" C, so arranged

25 that the axle will be rotated only in the forward movement of the machine, while in turning or backing the wheels are turned upon the shaft, as in the manner well known to manufacturers. Upon this shaft A is mounted a

30 suitable frame, D. At the rear portion of the frame, and near the sides thereof, are mounted the hoppers E, provided with feed-spouts F, which deliver the grain, as hereinafter described, into the furrow opened by the shoe

35 G in the forward movement of the machine. Each of these hoppers is provided with a feed-slide, H, the forward ends of which are provided with suitable eccentric straps for engaging with the eccentrics C', formed on the

40 axle A.

J is a follower in rear of the shoe G, and is adjustably secured to the frame D by the bars K.

Transversely across the machine are placed shut-off slides L, designed and arranged to be 45 simultaneously operated by a lever, M.

In practice, draft being applied to the front of the machine, the wheels B will rotate and impart a like motion to the axle. The cams operating upon the feed-slides deliver the desired amount of grain over the hopper to the feed-spout, from whence it falls into the furrow made by the shoe G, and in the further progress of the machine the follower J turns back the dirt thrown up by the shoe, thus covering 55 the grain, and this follower, by means of the vertical adjustment of its bar K, may be made to throw more or less of a covering over the grain, as may be desired. Supposing the wheels to be four feet in circumference and 60 the hoppers four feet apart, the machine in traveling the length of a row will have planted two rows of corn in hills four feet apart in each direction. Hoppers N may be placed in front 65 of the hoppers E and arranged to feed a fertilizer to the hill before the grain is dropped therein, such feeding of the fertilizer being performed by the feed-slides H.

If desired, the traction-wheels may be made of a larger dimension, so that four hills may be 70 planted at one revolution of the wheels.

What I claim as my invention is—

The combination, with the frame, axle, traction-wheels, and eccentrics on said axle, of the hoppers E, feed-spouts F, shoes G, feed-slides 75 H, connected directly with said eccentrics, the adjustable followers J to the rear of said shoes, the transverse slides L, the lever M, and connections between said slides and lever, all constructed, arranged, and operating substantially 80 as described, and for the purposes specified.

JOSEPH STEVENS.
